CLAIM

We claim the ornamental design for a top-side control panel for bathing unit, substantially as shown and described.

DESCRIPTION

FIG. 1 is a perspective view of a top-side control panel for bathing unit according to the design;

FIG. 2 is a front elevation view of the top-side control panel for bathing unit of FIG. 1;

FIG. 3 is a left side elevation view of the top-side control panel for bathing unit of FIG. 1, a right side elevation view being the same at the left side elevation view;

FIG. 4 is a top view of the top-side control panel for bathing unit of FIG. 1, a bottom view being the same at the top view; and,

FIG. 5 is a view of the top-side control panel for bathing unit of FIG. 1 shown mounted on the ledge of a bathing unit to illustrate a typical environment in which it would be used. In FIGS. 1-4 the broken lines depict a portion of the bathing unit that forms no part of the claimed design. In FIG. 5 the broken lines depict environment that forms no part of the claim.
